UNITED STATES PATENT OFFICE

RICHARD W. KRITZER, OF CHICAGO, ILLINOIS, ASSIGNOR TO PEERLESS ICE MACHINE COMPANY, OF CHICAGO, ILLINOIS

REFRIGERATION UNIT

Application filed February 20, 1929. Serial No. 341,523.

My invention relates to improvements in refrigeration units, and it consists in the combinations, constructions, and arrangements herein described and claimed.

5 An object of my invention is to provide a refrigeration unit in which novel displacement means is provided whereby a maximum cooling efficiency is attained with a minimum amount of refrigerant liquid.

10 A further object is to provide a refrigeration unit in which the displacement means is so arranged that a film of refrigerant liquid is provided around the internal walls of the refrigeration unit.

15 A further object is to provide a refrigeration unit in which the cover for the unit is provided with displacement means whereby a relatively simple construction is attained.

20 A further object is to provide a refrigeration unit of the type employing a float and in which a recess is provided and shaped to substantially conform to the contour of the float, whereby the latter will be actuated by a film of refrigerant liquid.

25 A further object is to provide a refrigeration unit of a type which will freeze ice cubes and the like in any one unit of a multiple unit refrigeration installation, and in which the freezing is attained in a minimum length of time.

30 Other objects and advantages will appear in the following specification and the novel features of the invention will be particularly pointed out in the appended claims.

35 My invention is illustrated in the accompanying drawing, forming part of this application, in which

Figure 1 is a sectional view taken along the line 1—1 of Figure 2,

40 Figure 2 is an end elevation partly in section of a refrigeration unit constructed in accordance with my invention, and

45 Figure 3 is a diagrammatic view of a refrigeration system employing my refrigeration unit.

In carrying out my invention, I make use of a main or float chamber 1 having an open end 2 and a flange portion 3 surrounding the open end. A cover 4 having a displacement member 5 formed integrally therewith is ar-

ranged to close the open end of the float chamber 1. The cover 4 is secured to the flange 3 by means of bolts or screws 6. The displacement member 5 is provided with a freezing chamber 7 and is disposed within the float chamber 1, as shown in Figures 1 and 2.

The displacement member 5 is proportioned so that a space 8 is provided between the displacement member and the walls of the float chamber 1. The cover 4 is provided with a boss 9 having a threaded opening 10 for receiving one end of a refrigerant liquid feed pipe. A passageway 11 places the opening 10 in communication with the interior of the float chamber 1, see Figure 1. In referring to Figure 1 it will be seen that I have mounted a float lever 12 upon the displacement member 5. The float lever 12 is provided with arm portions 13 pivotally mounted between bosses 14 by means of a pin 15. The float lever 12 is provided with an arm 16 having a valve 17 arranged for closing the passage 11.

The displacement member 5 is provided with a recess 18 substantially conforming to the shape of a float 19 connected with the float lever 12. The recess 18 is slightly larger than the float, whereby a space 20 is provided between the float and the walls of the recess. In referring to Figure 1, it will be seen that I have provided a passageway 21 for placing the recess 18 in communication with the space 8. The float chamber 1 is provided with a boss 22 having a threaded opening 23 for receiving one end of a vapor pipe as shown in Figure 3. Any suitable tray 24, see Figure 2, may be placed within the freezing chamber 7 for freezing ice cubes.

From the foregoing description of the various parts of the device, the operation thereof may be readily understood. Referring now to Figure 3, it will be seen that a vapor line 25 is connected with the float chamber 1 by reason of the threaded opening 23 and a compressor 26. The compressor is operated by a motor 27 connected with a source of current through conductors 28 and 29. A pipe 30 connects the compressor 26 with a condenser 31. The condenser is operatively connected with the vapor line 25.

connected with the float chamber 1 by means of a refrigerant liquid pipe 32 having one end disposed within the threaded opening 10. In operation when the compressor 26 is actuated, the refrigerant vapor will be forced into the condenser 31, where it is cooled and liquefied. The liquid is then conveyed from the condenser to the float chamber through the medium of the pipe 32 to the passage-way 11.

10 When a sufficient amount of liquid has passed into the float chamber 1 to fill the space 8, the passageway 21, and a part of the recess 18, the float 19 will be lifted. When a proper amount of refrigerant liquid has been forced into the float chamber, the float lever 12 will be lifted sufficiently far for moving the valve 17 into engagement with its valve seat, thereby closing the passageway 11.

15 Thus it will be seen that the valve 11 will stop the passage of the refrigerant liquid into the float chamber until such time as a sufficient amount of liquid has been vaporized, due to the operation of the compressor pulling the vapor through the pipe 25. After a certain amount of liquid has been vaporized, the liquid level will be such that the valve 11 will again permit the liquid to be passed into the float chamber. The construction of my 20 device is such that the float 19 is actuated for regulating the valve 11 in such a manner that the refrigerant liquid is permitted to pass into the float chamber in quantities equal to the amount of liquid vaporized.

25 I claim:

1. In a refrigerating system, a refrigeration unit comprising a float chamber for containing a refrigerant liquid, displacement means disposed within the float chamber and having an opening, and float-operated valve means disposed within the chamber for regulating the level of the liquid therein, said float being disposed within the opening and substantially conforming to the shape of the latter whereby the float will be actuated by the liquid film between the float and the walls of the opening.

2. In a refrigerating system, a refrigeration unit comprising a float chamber for containing a refrigerant liquid and being provided with an open end, a cover means for closing the open end of said float chamber, displacement means associated with said cover and disposed within the float chamber for providing a film of refrigerant liquid between the walls of the float chamber and the displacement means, and float-operated valve means for controlling the refrigerant liquid level within the float chamber, said displacement means being formed to provide a film of refrigerant liquid surrounding a portion of the float for actuating the latter.

3. In a refrigerating system, a refrigeration unit comprising a float chamber provided with a freezing chamber near its bot-

tom, said float chamber being provided with a depression above said freezing chamber, and float-operated valve means disposed within the float chamber for controlling the level of a refrigerant liquid therein, the float associated with said valve means being disposed within the depression and the contour of said depression being shaped to substantially conform to the shape of said float.

4. In a refrigerating system, a float chamber for containing a refrigerant liquid, displacement means disposed within the float chamber and being provided with a depression, and float-controlled valve means disposed within the float chamber for controlling the level of a refrigerant liquid within the float chamber, said displacement means being spaced away from the walls of said float chamber, the float associated with said valve means being disposed within said depression, said displacement means being provided with a passageway for placing said depression in communication with the space between the displacement means and the float chamber.

5. A refrigeration unit comprising a float chamber having an open end, a cover for closing said open end and being provided with displacement means spaced away from the walls of said float chamber, said displacement means being provided with a depression and an opening arranged for placing the depression in communication with the space between the displacement means and the float chamber, and float-controlled valve means for controlling the passage of a refrigerant liquid into the float chamber, the float associated with said valve means being substantially disposed within said depression.

6. A refrigeration unit comprising a float chamber having an open end, a cover for closing said open end and being provided with displacement means spaced away from the walls of said float chamber, said displacement means being provided with a depression and an opening arranged for placing the depression in communication with the space between the displacement means and the float chamber, and float-controlled valve means for controlling the passage of a refrigerant liquid into the float chamber, the float associated with said valve means being substantially disposed within said depression, said float chamber being provided with a passageway whereby the vaporized refrigerant liquid may be drawn from said float chamber.

7. A cooling unit comprising a casing having an open end, a cover for closing said open end, float operated valve means disposed within said casing, and a displacement element formed integrally with said cover arranged to provide a narrow space for a refrigerant between the walls of the shell and the displacement element and between the float associated with said valve means and the displacement element.

8. A cooling unit comprising a casing having an open end, a cover for closing said open end, said cover being provided with an inlet opening and the casing being provided with an outlet opening, float operated valve means for controlling the passage of refrigerant into said casing, and a displacement element formed integrally with said cover arranged to provide a narrow space for a refrigerant between the displacement element and the walls of the casing and between the float and said displacement element.

9. A cooling unit comprising a casing having an open end, a cover for closing said open end, said cover being provided with a displacement block having a freezing chamber and a depression, said displacement means being disposed within said casing for providing a narrow space for refrigerant between the displacement block and the walls of said casing when said cover is placed in position, the space above said displacement means being adapted for a float chamber, float controlled valve means associated with said cover and the displacement block for controlling the passage of refrigerant into said casing, the float associated with said float controlled valve means being disposed within said depression and operated by a film of refrigerant between the float and the walls of the depression, said cover being provided with an inlet opening controlled by said valve means and the casing being provided with an outlet opening, and means for securing the cover to said casing.

10. A cooling unit comprising a casing having an open end, a cover for closing said open end, said cover being provided with a displacement block having a freezing chamber and a depression, said displacement means being disposed within said casing for providing a narrow space for refrigerant between the displacement block and the walls of said casing when said cover is placed in position, the space above said displacement means being adapted for a float chamber, float controlled valve means associated with said cover and the displacement block for controlling the passage of refrigerant into said casing, the float associated with said float controlled valve means being disposed within said depression and operated by a film of refrigerant between the float and the walls of the depression, and means for removably securing the cover to said casing.

11. In an evaporator having float operated valve means and an open end, a cover for closing said open end, said cover being provided with a displacement element arranged to provide a film of refrigerant between the walls of the evaporator and the displacement element and between the latter and the float associated with said float operated valve means.

12. In an evaporator having float operated

valve means and an open end, a cover for closing said open end, said cover being provided with a displacement element arranged to provide a film of refrigerant between the walls of the evaporator and the displacement element and between the latter and the float associated with said float operated valve means, said displacement element being provided with a cooling chamber.

13. A cooling unit comprising a shell provided with a float operated valve mechanism, and displacement means arranged to provide a narrow space for a film of refrigerant between the walls of the shell and the displacement means and between the latter and the float associated with said float operated valve mechanism.

14. In a cooling unit having a float chamber, displacement means disposed within the float chamber and having a recess, and float operated valve means disposed within the chamber and having its float disposed within said recess, said recess being of such dimension with respect to the float that the latter will be actuated by a relatively small quantity of refrigerant.

15. A cooling unit comprising a housing having an open end, a cover for closing said open end and having a displacement member positioned within the housing, said displacement member being provided with a float recess and a freezing chamber, and float operated valve means for controlling the flow of a refrigerant into said housing, the float being positioned within said recess, said recess being of such dimension with respect to the float that the latter will be actuated by a relatively small quantity of refrigerant.

16. In a refrigerating system, a refrigerating unit comprising a float chamber having an open end, a cover for closing the same, displacement means associated with said cover and arranged for providing a space for a film of refrigerant liquid between the displacement means and the walls of the float chamber, said displacement means being provided with a depression, and float-operated valve means for controlling the level of the refrigerant liquid within the float chamber, the float associated with said valve means being disposed within said depression for providing a space for a film of refrigerant liquid between the float and the walls of said depression.

17. In a refrigerating system, a refrigerating unit comprising a float chamber having an open end, a cover for closing the same, displacement means associated with said cover and arranged for providing a space for a film of refrigerant liquid between the displacement means and the walls of the float chamber, said displacement means being provided with a depression, and float-operated valve means for controlling the level of the refrigerant liquid within the float chamber,

the float associated with said valve means being disposed within said depression for providing a space for a film of refrigerant liquid between the float and the walls of said depression, said displacement means being provided with a passageway for placing said depression in communication with the space between the walls of the float chamber and the displacement means.

10 Signed at Chicago, in the county of Cook, and State of Illinois this 7th day of February, A. D. 1929.
